FLIGHT COMPUTER

Lewis W. Imm, Glendale, Calif., assignor to
 Librascope, Incorporated, Burbank, Calif., a
 corporation of California

Application April 21, 1942, Serial No. 439,874

11 Claims. (Cl. 235—61)

1

The present invention relates to computing mechanisms and more particularly to the provision of correlated but individual computing devices capable of solving various portions of a complex problem which may involve, for example, the solution of various equations, solving one or several triangles to find the values of unknown sides or angles, the conversion of polar to rectangular coordinates, and other computations.

The computations involved in aircraft flight problems are complex computations of this nature, and the invention is disclosed as embodied in a flight computer because it is important to provide a computer which will rapidly and accurately solve such problems while in flight. It will be understood, however, that many of the subcombinations disclosed herein are useful in computing devices designed for other or more general uses.

A principal object of the invention is the provision of improved mechanisms for solving equations of a complex nature.

A further principal object of the invention is the provision of a novel mechanism for computing the conversion of polar coordinates to rectangular coordinates.

Further and more specific objects of the invention are the provision of triangle solving mechanisms by which, given the values of two sides and a non-included angle the value of the other non-included angle or the value of the third side may be computed.

Additional specific objects of the invention include solving for value of true airspeed, drift angle, distance travelled in a given time and similar values, from known or indicated data available to aircraft pilots.

Other objectives and advantages are given in the detailed specification and claims which follow. The invention may be better understood by referring to the attached drawings in which:

Fig. 1 is a view in frontal elevation of the control panel of an instrument embodying the present invention.

Fig. 2 is a rear view of the complete computing mechanism.

Fig. 3 is a rear elevational view of the true airspeed and time mechanisms.

Fig. 3A is a rear view of one of the multiplying mechanisms shown in Fig. 3 with the parts being in different positions.

Fig. 3B is a side elevational view showing one of the actuating springs and associated parts

2

designed to urge its associated pointer in the desired direction.

Figs. 3C, 3D, and 3E are rear elevational views of three of the multiplying mechanisms shown in Fig. 3 with the parts being in different positions from that shown in Fig. 3.

Fig. 4 is a rear elevational view of the wind direction and wind velocity mechanisms.

Figs. 4A and 4B are rear elevational views of two of the multiplying mechanisms shown in Fig. 4 with the parts being in different positions.

Fig. 5 is a rear elevational view of the altitude and air temperature mechanisms.

Fig. 6 is a detailed cross-sectional view of one of the setting knobs and the parts immediately actuated thereby.

Fig. 6A is a view similar to Fig. 6 but taken at right angles thereto.

Fig. 7 is a frontal view of the true course disc 20 and the wind direction knob.

Fig. 8 is a geometrical diagram to show the relationship of certain angles and lines.

In Fig. 8 is shown a geometric figure to better understand some of the problems involved and 25 the solution thereof. In this figure the line AN represents a true north and south line. Suppose the wind is blowing from B in the direction A or at an angle W relative to AN, and at a velocity V_w in a unit of time equal to the length of the

line AB. The desired course to be flown is in the direction E from the point A, making an angle C, with the line AN. The plane would be directed along this path if there were no wind to cause it to drift. Suppose we desire to follow 30 the line AE to the point F in a certain unit of time. Call this distance AF (V_g). V_g is then the true course ground speed in miles per hour. Draw FO from point F equal to and parallel to AB. Draw OB which will be parallel and equal to line

AF. Draw a perpendicular from the point O to the line AF, extended if necessary, meeting the line AF at the point E so that the angle E is a right angle. If F is between the points A and E then EA equals V_g+EF. If the point E lies between A and F; that is, if F is beyond the point E, then EA=V_g-EF. Therefore EA equals V_g±EF.

Draw the transversal AO of the parallelogram AFOB. Call this transversal V_a, representing the velocity of the plane, with respect to the surrounding air V_a being the resultant of the forces which are represented by the lines AF and AB. Line AO then represents the direction in which the plane must be headed to compensate for the wind condition. Call the angle FAO (D) which represents the drift angle and gives us the correc-

50 55

tion which we must make to true course to establish airplane heading AO. Call the angle EAB ($C-W$) which simply gives you a negative value for what would have a positive value in degrees if the expression had been ($W-C$). Since the line FO is parallel to AB and cut by the transversal EA, the angle EFO is equal to ($C-W$). C , W , and V_w are known quantities which are set up on the apparatus. V_a is a function of indicated air speed, temperature and altitude; all of which are known. A subsidiary computing mechanism is provided in the apparatus whereby V_a can be set up therein after the setting of temperature and altitude factors by observing scale 19, and matching the indication thereon with the known indicated air speed. The unknown quantities to be determined are V_g (actual ground velocity at which the plane is flying toward its destination), and D (the drift angle). Since total distance traveled toward a given destination is a product of V_g by time, it is obtained by entering the known time factor in the apparatus.

In the triangle

$$EOF \sin (C-W) = \frac{EO}{FO} \text{ or } \frac{EO}{V_w}$$

Therefore, $EO = V_w \sin (C-W)$.

In the triangle

$$AEO \sin D = \frac{EO}{V_a}$$

Therefore,

$$\sin D = \frac{V_w \sin (C-W)}{V_a}$$

so that

$$D = \sin^{-1} \frac{V_w \sin (C-W)}{V_a}$$

Formula #1.

In triangle FOE,

$$\cos (C-W) = \frac{EF}{V_w}$$

Therefore, $EF = V_w \cos (C-W)$.

In triangle EAO,

$$\cos D = \frac{EA}{V_a} = \frac{V_g \pm EF}{V_a}$$

Therefore,

$$\cos D = \frac{V_g \pm V_w \cos (C-W)}{V_a}$$

$$\cos D \pm \frac{V_w \cos (C-W)}{V_a} = \frac{V_g}{V_a}$$

Therefore,

$$V_g = V_a \left\{ \cos D \pm \frac{V_w \cos (C-W)}{V_a} \right\}$$

Therefore, $V_g = V_a \cos D \pm V_w \cos (C-W)$. But, $V_a \cos D = V_a + V_a (\cos D - 1)$.

Therefore, $V_g = V_a + V_a (\cos D - 1) \pm V_w \cos (C-W)$. Formula #2.

In order to simplify the construction of the mechanism whereby true air speed is computed, which computation requires that changes in air density at different altitudes and temperatures enter into the computation in accordance with the known formula:

$$V_i = V_a \sigma^{\frac{1}{2}}$$

this formula is alternatively expressed:

$$V_i = V_a + V_a (\sigma^{\frac{1}{2}} - 1) \text{ (Formula No. 3)}$$

thus permitting the feeding in of the relatively small quantity:

$$V_a (\sigma^{\frac{1}{2}} - 1)$$

as a corrective factor.

It having been ascertained that:

$$(\sigma^{\frac{1}{2}} - 1) = f(h, ta)$$

where $f(h, ta)$ represents a function of altitude and air temperature; it becomes necessary only to multiply this function by V_a in order to compute the quantity to be added, as a correction, to V_a to compensate for changes in air density at various altitudes and temperatures.

Also, the total distance (d) is the true course 15 ground speed V_g multiplied by time (t) or $d = V_g t$. Formula #4.

In all the four formulae above, V_g = true course ground speed in miles per hour.

V_a = true airspeed in miles per hour.

D = drift angle in degrees.

V_w = wind velocity in miles per hour.

C = course or track to be flown in degrees; i. e., the course that would be flown by the plane if there were no drift.

W = wind direction in degrees.

V_i = indicated airspeed in miles per hour.

σ = density ratio of air under actual conditions which, of course, is controlled by altitude and air temperature.

30 d = total distance in miles.

t = time in hours.

All of the setting knobs or item-entering devices, as well as all of the links, levers, and other 35 movable parts, are mounted on a main panel 157. The face plate 157' is spaced a slight distance in front of the panel 157, providing sufficient space therebetween for the various pointers.

In Figs. 6 and 6A the setting knob 159, which 40 is typical of all of the setting knobs 163, 164, 165, 167, 168, and 170, is affixed to shaft 158, rotatably mounted on panel 157. On the back of panel 157 a pinion 160 is secured to the shaft 158, which pinion meshes with and drives a rack 45 161, which is maintained in mesh with the pinion 160 by means of a spring clip 162. The rack 161 carries a plate 173, to which is secured a pull-push wire 174. The arrangement is such that rotation of the knob 159 will reciprocate the rack 50 161, and in order to prevent inadvertent displacement thereof after the knob 159 has been set, the spring clip 162 presses the rack 161 into engagement with pinion 160, thereby creating sufficient friction to prevent movement of the 55 rack 161 or the wire 174 unless knob 159 is positively rotated. All of the setting knobs shown in Fig. 1 operate racks and wires similar to the above described mechanisms in Figs. 6 and 6A.

True airspeed knob and mechanisms controlled thereby

60 The true airspeed factor V_a is set into the instrument by rotating the true airspeed knob 163. As shown in Fig. 3, rotation of the true airspeed knob 163 turns gear pinion 1, corresponding to pinion 160, which moves rack 2, corresponding to rack 161. At this point the motion splits into two parts, one part following wire 4 and the other part following the movement of pin 7 carried by the lower end of rack 2. Wire 70 4 is secured to the plate 173 which corresponds to the plate 173 of Fig. 6.

The pin 7 actuates the lever 6 an amount corresponding to V_a . The lever 6 turns on pin 22 which is carried by the link 142, Fig. 4. While 75 it is true that the pin 22 is actuated by the wind

direction and wind velocity knobs, as will be hereinafter described, the pin 22 is stationary while only the pinion 1 is rotated, so that it may be considered as a fixed pivot pin. As pin 7 moves upwardly or downwardly, as above described, it moves lever 5, the pin 7 serving as a means to connect the lower portion of rack 2 to both levers 5 and 6. The lever 5 is pivoted on pin 18, which is movably supported by wire 69 and which is given a movement corresponding to $V_a(\sigma^{1/2}-1)$, as will be hereinafter described. The lever 5 carries the pin 9 intermediate its ends, and the wire 8 extends upwardly from the pin 9. The lever 5 is an addition lever which adds the value V_a received from pin 7 to $V_a(\sigma^{1/2}-1)$ received from pin 18 so that the wire 8 is given a movement corresponding to

$$V_a + V_a(\sigma^{1/2}-1)$$

which is indicated airspeed V_i . Formula 3. Motion is transmitted from wire 8 to lever 11 through pin 12, with lever 11 having a fixed pivot on the pin 13 carried by the panel 157. Lever 11 moves wire 14 by means of pin 15. Wire 14 carries stop 176 at its upper end above disc 177 through which the wire slides. The disc 177 is rotatably mounted on pin 17 carried by lever 16, which is secured to shaft 18, to which is attached the indicated airspeed pointer 19.

A conventional coil spring 178, Fig. 3B, is wound about shaft 18, having one end connected to the panel 157 and the other end embedded in nut 180 secured to shaft 18, so as to urge lever 16 clockwise or towards the stop 176. It is therefore apparent that a lost motion connection is provided between the wire 14 and lever 16. When the wire 14 moves upwardly, with the lever 16 spaced below the stop 176, the lever 16 moves clockwise and the disc 177 is held against stop 176 by means of the spring 178. The lever 16 engages the stop 176 when pointer 19 is at the lowest reading of the indicated airspeed scale. However, the wire 14 may continue its upward movement even after the lever 16 is stopped by the stop 176, but in this case the wire 14 simply slides through the hole of the disc 177 so that stop 176 would travel away from the disc 177 and no motion would be imparted to the lever 16 or pointer 19. When the wire 14 is then moved downwardly it would impart no motion to the lever 16 until the stop 176 engages the disc 177, and thereafter the downward movement of wire 14 would rotate the lever 16 and the pointer 19.

It will be remembered that lever 6, pivoted on pin 22, is also actuated by movement of the rack 2 by which the lever 6 is given a movement of V_a at pin 7. As will hereinafter be explained, the pin 22 is given a movement corresponding to $V_w \cos(C-W)$. Lever 6 carries pin 21 on which lever 20 is mounted and this pin is therefore moved an amount corresponding to $V_a + V_w \cos(C-W)$. The lever 20 carries movable pin 25 supported by the lower end of wire 77, which is also movable when the pinion 1 is actuated and is given a movement corresponding to $V_a(\cos D-1)$, as will be hereinafter described. Lever 20 is provided with pin 24, the movement of which will, therefore, depend upon the movement of both pins 21 and 25 and hence will be moved an amount corresponding to

$$V_a(\cos D-1) + V_a + V_w \cos(C-W)$$

which is V_g or true course ground speed in miles per hour. Formula #2. Pin 24 actuates wire 23 which moves lever 26 by means of pin 27, with lever 26 having a fixed pivot pin 28 secured to

the panel 157. At this point the motion splits into two parts, one part following wire 29 through pin 30 and the other part following wire 31 through pin 32.

- 5 Rotatable on pin 32, carried by lever 26, is a disc 181 having a hole through which extends a wire 31 which carries a stop 182 below the disc 181, which stop is resiliently held in contact with disc 181 by means of the spring 183 coiled about wire 31 and interposed between a stop 184 on wire 31 and disc 185. The disc 185 is rotatably mounted on pin 34 carried by lever 33 secured to shaft 35. The disc 185 is provided with a hole through which the wire 31 extends and the wire 31 is provided with a stop 186 below the disc 185. A coil spring, identical with spring 178, is coiled about shaft 35, having one end embedded in panel 157 and the other end connected to a nut similar to nut 180 secured to shaft 35, which carries the true course ground speed pointer 36. As above stated, the rod 23 is actuated by the pin 24 an amount corresponding to true course ground speed or V_g , and this movement is transmitted to pointed 36 by the means above described. The lever 33 has a tail extending beyond the shaft 35, and when the true course ground speed pointer 36 is at its lowest reading of its scale, the said tail contacts the fixed stop 188. The coil spring around shaft 35 urges the lever 33 clockwise so as to urge the tail 33 into engagement with the stop 188 and so as to urge the disc 185 into engagement with stop 186 on wire 31. The objective of the above described lost motion connection is to stop pointer 36 at its lowest reading relative to its scale while allowing lever 26 to continue its downward movement.

It will also be remembered that when lever 26 is actuated it moves a wire 29 by means of the pin 30 an amount corresponding to V_g . The upper end of the wire 29 is connected to a bell crank lever 37 by means of pin 38. The bell crank lever 37, Figs. 3 and 3A, has a fixed pivot pin 39, and the said lever extends upwardly beyond the pivot pin to the pin 41. The link 40 is also hung on the pin 41, and the lower end of the link 40 carries a pin 42 connected to links 44 and 43. The link 43 is pivoted on pin 45 carried by the upper end of lever 104 mounted on a fixed pivot 103, which lever 104 is connected to rod 103 by means of pin 105. The rod 103 is connected to rack 102, geared to pinion 101 actuated by the time knob 164 so that the pin 42 is given a movement corresponding to time t . The link 44 is connected to the lever 47 by means of pin 46, lever 47 having a fixed pivot on pin 48 carried by panel 157. A spring 3 is connected to lever 37 so as to tend to rotate the said lever in a clockwise direction to take out any possible backlash. The parts including the links 40, 44 and 37 of Fig. 3A is a multiplying mechanism by which the value t or time entered by means of link 43 is multiplied by true course ground speed V_g entered through lever 37, which product is total distance d . Formula #4.

As shown in Fig. 3, the pins 39 and 42 are in alignment with each other. In such a case, the rotation of the bell crank lever 37 moves pin 41 and lever 40 without moving link 44. This condition would occur when the time setting knob 164 is at zero. However, when the time setting knob 164 is actuated the lever 104 is moved, moving the pin 45, as will be hereinafter described, so that pin 42 is moved out of alignment with pin 39. This condition is shown in Fig. 3A.

Considering the parts in the position shown in Fig. 3A, it is apparent that if lever 37 were moved clockwise on pin 39, pin 41 will be moved in an arc of a circle having a radius equal to the distance between the pins 39 and 41. Since the pin 45 is not being moved it may be considered as a fixed pivot for it will not be moved until the time setting knob 164 actuates it. Therefore, the pin 42 can only move in an arc of a circle having a radius equal to the distance between pins 45 and 42. Link 40 will therefore, move downwardly. As pin 42 moves downwardly with link 40, link 44 will be pulled downwardly, and the bell crank lever 47 will move anti-clockwise on its fixed pivot pin 48. These motions, of course, will be reversed when the bell crank lever is moved anti-clockwise.

The bell crank lever 47 at its other end carries a pin 50 which will be moved an amount corresponding to total distance d as above described. On this pin 50 is rotatably mounted a disc 189 having a hole through which passes the wire 49, carrying stop 190 below the disc 189. As there is extremely little lost motion at this point the wire 49 may be considered as a link suspended from pin 50. The wire 49 is connected to lever 51 by pin 52. The lever 51 is secured to shaft 53, on which is secured the total distance pointer 54. A coil spring, similar to spring 179, surrounds shaft 53, and tends to urge the pointer 54 towards its highest reading.

It will be remembered that, when the pinion 1 is rotated, the wire 4 is raised. The link 55 is rigidly attached to wire 4, and at its upper end carries a wire 191 slidably through a hole in a guide 192. The link 55 actuates link 56 through pivot pin 57, link 58 through pivot pin 59, and link 60 through pivot pin 61. All of the pins 57, 59, and 61 will be actuated by link 55 an amount corresponding to V_a .

The link 56 Figs. 3 and 3C carries pin 64 at its upper end, which pin is connected to links 62 and 63. Link 63 is connected to bell crank lever 67 by means of pin 66. The bell crank lever 67 is pivoted on fixed pin 68. Link 62 is connected to link 152 mounted on a fixed pivot pin 153 by means of pin 65, which pin, as will be hereinafter described, passes through the upper end of wire 150, which may be shifted by either the altitude knob or the air temperature knob and which wire 150 is given a movement corresponding to $\sigma^{\frac{1}{2}}-1$, as will now be explained. The altitude factor is set into the instrument by manually operating the altitude knob 168. As shown in Fig. 5, rotation of the altitude knob 168 turns the pinion 201 which moves rack 202 which carries wire 203. Wire 203 moves lever 147 through pin 148, with lever 147 being pivoted on a pin 149, which may be moved by the air temperature knob 170. The air temperature knob 170 actuates pinion 154 which actuates rack 155, carrying wire 156 connected to pin 149. Therefore, when pinion 154 is actuated the lever 147 has a fulcrum on pin 148, and when pinion 201 is actuated the lever 147 has a fulcrum on pin 149. Lever 147 carries a pin 151 which actuates the wire 150, which is connected by pin 65 to links 62 and 152, constituting a part of the multiplying mechanism described in connection with Fig. 3C. As explained in connection with Formula 3, $\sigma^{\frac{1}{2}}-1$ is a function of altitude and air temperature, and the wire 150 and pin 65 are therefore actuated an amount corresponding to $\sigma^{\frac{1}{2}}-1$.

This multiplying mechanism shown in Fig. 3C

multiplies the value V_a entered through pin 57 by $\sigma^{\frac{1}{2}}-1$ entered through wire 150. As shown in Fig. 3, pins 65 and 66 are spaced only a short distance apart. If the pin 65 were in alignment with the pin 66, and the link 55 were actuated to move links 62 and 63, no motion would be imparted to the bell crank lever 67. But the pins 65 and 66 may be moved a considerable distance apart, as shown in Fig. 3C, by the altitude and air temperature knobs. As shown in Fig. 3C, the upward movement of link 55 moves the pin 64 upwardly, thereby moving the lefthand ends of links 62 and 63. Unless the wire 150 is also shifted, the pin 65 may be considered as a fixed pivot for it is held against vertical movement by wire 150 and against lateral movement by link 152, so that the pin 64 will describe an arc of a circle having a radius equal to the distance between the pins 64 and 65. As pin 64 moves upwardly on this arc it pulls the link 63 and rotates lever 67 clockwise. On the downward movement of pin 64 the motion described above will be reversed. Obviously if pins 65 and 66 were in alignment, the upward or downward movement of link 55 would impart no movement to lever 67. The greater the distance between pins 65 and 66 the more movement will be imparted to lever 67 by the raising or lowering of link 55. These parts therefore, constitute a multiplying mechanism so that the movement of lever 67 is dependent upon the movement of link 55 and the movement of wire 150 to position pin 65 further from or closer to pin 66.

Lever 67 moves wire 69 through pin 70'. Wire 69 moves lever 5 through pin 10 and this movement is $V_a (\sigma^{\frac{1}{2}}-1)$. It is, therefore, apparent that both ends of lever 5 are shifted when the pinion 1 is rotated. The lefthand end or pin 7 is shifted by rack 2 an amount corresponding to V_a , and the righthand end or pin 10 is shifted by wire 69 an amount corresponding to $V_a (\sigma^{\frac{1}{2}}-1)$. The pin 7, therefore, moves a distance exactly corresponding to the rotation of pinion 1, while the pin 10 is moved a distance corresponding not only to the rotation of pinion 1 but varied in accordance with the position of pin 65 relative to pin 66, which pin 65 is adjusted by the altitude knob 168 and the air temperature knob 170, as heretofore described. The lever 5 is an addition lever, so that the pin 9 will move an amount corresponding to $V_a + V_a (\sigma^{\frac{1}{2}}-1)$, which is the indicated air speed (V_i), as set forth by Formula No. 3. As heretofore described, the pin 9 is connected to the indicated airspeed pointer 19 through lever 11.

It will be remembered that link 58, Fig. 3D, moves with link 55 an amount corresponding to V_a . Link 58 moves links 70 and 71 by means of pin 72. Link 70 is pivoted to arm 75 by means of pin 73 and link 71 is pivoted to lever 97 by means of pin 74, lever 97 having a fixed pivot pin 99 carried by the panel 157 and arm 75 being mounted on a fixed pivot 76. The lever 97 carries a pin 98, on which is hung a wire 91, which wire 91 may be raised or lowered by the partial rotation of the lever 86. The essential point is that the raising or lowering of wire 91 rotates the lever 97 on its fixed pivot pin 99 an amount corresponding to $\cos D-1$ to move the pin 74 into or out of alignment with pin 73, the value $\cos D-1$ being zero when pin 74 is in alignment with pin 73. When wire 91 is raised it moves pin 98 upwardly and rotates lever 97 clockwise on its fixed pivot pin 99, and moves pin 74 downwardly, thereby varying its distance from pin 73. When

pins 73 and 74 are in alignment with each other and link 58 is raised or lowered, no movement is thereby imparted to arm 75, which has a fixed pivot 76; but the further the pin 74 is raised or lowered, relative to the pin 73, the greater is the movement which will be imparted to arm 75 by movement of the link 55. Here again we have a multiplying mechanism depending on the movement of pinion 1 and on the movement of wire 91, which is controlled by the movement of lever 83, as will be hereinafter described.

This multiplying mechanism multiplies the value V_a entered through link 58 by $\cos D-1$ entered through lever 97. The true airspeed knob 163 through pinion 1, as well as the wind direction knob 165, and the wind velocity knob 167, controls the movement of the lever 83.

Arm 75 moves wire 77 by means of pin 18'. Wire 77 is connected to lever 20 by means of pin 25. It is, therefore, apparent that lever 20 is controlled by both pins 21 and 25, that pin 25 is controlled by the position of the wind direction knob 165, as well as by the movement of the true airspeed knob 163 and the wind velocity knob 167 to enter the product $V_a (\cos D-1)$, while pin 21 is actuated an amount corresponding to $V_a + V_w \cos (C-W)$ because it is controlled by the movement of both pin 7 and pin 22, the pin 7 being controlled solely by the true airspeed knob 163 and hence introducing the value V_a , while the pin 22 is controlled by the wind direction knob 165 and the wind velocity knob 167 and entering the value $V_w \cos (C-W)$, as will be hereinafter described. The actuating of wire 23 by pin 24 is, therefore, dependent upon all of the above factors so that this wire moves an amount corresponding to $V_a (\cos D-1) + V_a + V_w \cos (C-W)$, or true course ground speed, which is V_g . Formula #2; and it will be remembered that it is the wire 23 that actuates the true course ground speed pointer 36 and the total distance pointer 54, as heretofore described.

It will be remembered that the vertical movement of link 55 moves the pin 61 and link 60 upwardly or downwardly an amount corresponding to V_a . Referring to Fig. 3E, it will be noted that the pin 80 connects links 78 and 79 to the upper end of link 60. The other end of link 78 is connected to lever 127 by means of pin 81. The lever 127 has a fixed pivot pin 129 and may be partially rotated on its pivot pin 129 by the movement of pin 128, which is actuated by the rotation of the wind direction knob 165 and the wind velocity knob 167 an amount corresponding to $V_w \sin (C-W)$, as will be hereinafter described. The righthand end of link 79 is connected to lever 83 by means of pin 82. The lever 83 has a fixed pivot pin 100 carried by panel 157, which lever extends beyond the pin and at its lefthand end carries a pin 85 on which is mounted disc 193. This mechanism shown in Fig. 3E is a division mechanism which divides $V_w \sin (C-W)$ entered through pin 128 by V_a entered through link 60. However,

$$\frac{V_w \sin (C-W)}{V_a} = \sin D$$

Formula #1. As shown in Fig. 3, the pins 81 and 82 are in alignment with each other, and the vertical movement of link 55 will partially rotate links 78 and 79 without imparting any movement to lever 83. As will be hereinafter explained, if the wind direction knob 165 were rotated clockwise from the position shown in Fig. 1, for 90°, and if the wind velocity knob 167 were set to

represent a value, the lever 127 will be actuated so as to move anti-clockwise, thereby moving pin 81 to the right. It pulls link 78 and moves pin 80 to the right, thereby pushing link 79 and rotating lever 83 clockwise. If the wind velocity knob 167 were set at zero the rotation of knob 165 would not move the lever 127, as will be hereinafter described. Since link 79 is connected to lever 83, and since lever 83 has a fixed pivot on 100, the pin 82 is moved downwardly to the position shown in Fig. 3E. If then the link 55 were actuated, movement would be imparted to lever 83. The extent of this movement would depend on how far link 55 was moved and how far out of alignment were pins 81 and 82, and this would depend on the setting of the wind direction knob 165 and the wind velocity knob 167.

If the wind direction knob 165 had been rotated anti-clockwise instead of clockwise, as above described, and if the wind velocity knob 167 were moved to represent a value, the pin 82 would be moved above the pin 81, as will be hereinafter described. The wind velocity knob 167 and the wind direction knob 165 control the position of pin 81, while the true airspeed knob 163 controls the link 55. This is a division mechanism having as its factors true airspeed, wind velocity, and wind direction.

The lefthand end of lever 83 is, therefore, moved upwardly or downwardly, as above described an amount corresponding to the value of $\sin D$, carrying the pin 85 and the disc 193 with it. A wire 84 slides through a hole in disc 193. The wire 84 carries a stop 194 below the disc 193 and a stop 195 spaced a distance above the disc 193, with a spring 196 coiled about the wire 84 and interposed between the stop 195 and the disc 193. The lower end of wire 84 passes through a hole in disc 197 mounted on pin 87, and carries a stop 198 below said disc. The wire 84 also carries a stop 199 spaced above the disc 197, and a spring 200 is coiled about the wire 84 and is interposed between the stop 199 and disc 197.

There is, therefore, a lost motion connection 45 between the lever 83 and the wire 84, and also between the wire 84 and the disc 197. The disc 197 is mounted on a pin 87 carried by bell crank lever 86 pivoted on a fixed pin 88. The lever 86 is connected to the lower end of wire 91 by pin 92, which wire 91, as above described, is connected to lever 97, which controls the relative position of pins 73 and 74 and, therefore, controls the degree of movement which will be imparted to wire 77 when link 55 is moved by pinion 1. In Fig. 3 it will be noted that the angle formed between the lines passing through the points 87 and 88 and 88 and 92 is slightly more than a right angle. If it were a right angle, then the vertical movement of $\sin D$ given to the pin 87, as heretofore described, would impart a vertical movement to rod 91 through pin 92 of $\cos D$, but since the said angle is slightly greater than a right angle, the said vertical movement of the rod 91 is $\cos D-1$, which movement is trans-

65 mitted to the pin 98 of lever 97. Also, it will be remembered that the link 58 of Fig. 3D entered a value of V_a , and that the multiplying mechanism of that figure actuates the rod 77 an amount corresponding to their product, which 70 is $V_a (\cos D-1)$. Since wire 77 controls the variable pivot pin 25, it thereby controls in part the true course ground speed pointer 36 and the total distance pointer 54.

The lever 86 also carries a pin 90 which actuates wire 89 which moves arm 93 by means of pin

94. Arm 93 turns the drift angle pointer shaft 95, to which is attached the drift angle pointer 96, Fig. 1. Since the vertical movement of pins 87 and 99 of lever 86 correspond to the sin value of the drift angle D, as above described, the arm 93 converts this sin movement into the angular value of the drift angle D.

True course disc and wind direction knob

The true course disc 166, Figs. 1 and 7, is merely a compass rose. The true course disc 166 is manually turned about its pivot and moves none of the linkage mechanism whatsoever.

The wind direction disc 171 is rigidly attached to the wind direction knob 165. The difference between the true course angle and the wind direction angle (C-W) is accomplished with the true course disc 166 and the wind direction knob 165. The procedure is as follows: The true course disc 166 is rotated manually so that the value in degrees of the true course is directly indicated by the true course arrow 172. For example, in Fig. 7, 30° was indicated as the true course. The wind direction knob 165 is then rotated to indicate the wind direction relative to the true course disc 166. As shown in Fig. 7, 60° is indicated as the wind direction. The wind direction knob 165 is secured to shaft 107 which carries crank 108. When the wind direction knob 165 points directly to the fixed arrow 172 the crank 108 on crank shaft 107 is in its zero position. It can now be seen on Fig. 7 that the wind direction knob 165 has been positioned at an angle of 30° relative to the true course disc 166, this being the difference between the true course angle and the wind direction angle. In other words,

$$(C-W) \text{ equals } 30^\circ - 60^\circ = -30^\circ$$

and the crank shaft therefore, has rotated 30°, and places the proper rotation into the mechanism (C-W).

Wind direction and wind velocity knobs and mechanisms controlled thereby

As above described, the knob 165 rotates the crank 108 an amount corresponding to C-W. Crank 108 actuates wire 109 by means of pin 110 and also moves wire 111 by means of pin 112. It will be noted in Fig. 4 that the imaginary lines between the points 110 and 107 and 112 and 107 form a right angle at point 107, and that when the crank is in its zero position, as shown, the wire 111 is parallel to the line between the points 107 and 112. Therefore, the movement imparted to the wire 109 will be sin (C-W), and the movement imparted to the wire 111 will be cos (C-W). Wire 109 actuates link 113, Fig. 4A, by means of pin 114 with link 113 having a fixed pivot 115. Link 113 is connected to link 116 by means of pin 117. Link 116 is connected to links 118, 119 by means of pin 120 with link 118 being pivoted on pin 121 carried by reciprocating link 146 and link 119 being pivoted on pin 122 carried by lever 123, which lever 123 is mounted on a fixed pivot 124. The link 146 is actuated by the wind velocity knob 167 through pinion 143, rack 144 and wire 145 an amount corresponding to V_w so as to vary the distance apart of pins 115 and 120, thereby entering the value V_w or the wind velocity into the multiplying mechanism shown in Fig. 4A, and the rod 109 enters the other multiplying factor sin (C-W). Lever 123 is the output for the multiplying mechanism and is therefore actuated an amount corresponding to V_w sin (C-W). Lever 123 actuates wire 125 through

126. Wire 125 actuates lever 127 by means of pin 128, the lever 127 having a fixed pivot 129. As heretofore described in connection with Fig. 3E, lever 127 actuates link 78 through pin A-1, and the output from the division mechanism shown in said Fig. 3E is the rod 34 which is actuated an amount corresponding to

$$\frac{V_w \sin (C-W)}{V_a}$$

It will be remembered that the rod 34 leads to mechanism controlling the drift angle pointer 96, the true course ground speed pointer 36 and the total distance pointer 54.

It will be remembered that when the wind direction knob 165 is rotated, thereby rotating crank 108, wire 111 is actuated an amount corresponding to cos (C-W). The wire 111 moves link 130, Figs. 4 and 4B, by means of pin 131, with link 130 having a fixed pivot pin 132. Link 130 is connected to link 133 through pin 134. Link 133 is connected to link 135 and link 136 through pin 137, with link 135 being pivoted on pin 138 carried by link 146, which is actuated an amount corresponding to V_w by the wind velocity knob 167. Link 136 is connected to the arm 140 by means of pin 139, with arm 140 having a fixed pivot pin 141. Arm 140 moves wire 142 through pin 143.

Here again we have a multiplying mechanism which moves the wire 142 according to the factors of wind velocity and wind direction. The link 135 introduces the factor V_w and the rod 111, the factor cos (C-W). This multiplying mechanism multiplies these factors and actuates the output rod 142 leading to the pin 22 of lever 6, Fig. 4, an amount corresponding to V_w cos (C-W). If the wind velocity knob 167 is at zero, the pins 137 and 132 will be in alignment, as shown in Fig. 4, and rotation of the wind direction knob 165 will impart no motion to the arm 140 or to the wire 142. When the wind velocity knob 167 is rotated to its maximum value the link 146 is raised, thereby moving pin 137 a considerable distance from the fixed pivot pin 132, as shown in Fig. 4B. If now the wind direction knob 165 were rotated from its vertical position, the wire 142 will be actuated according to both the wind direction and the wind velocity. When the wind direction knob 165 is rotated 90° from the position shown in Fig. 1 either to the right or to the left, the wire 111 will move link 130 so that the position of pins 134 and 139 are in alignment with each other. If now the wind velocity knob 167 were rotated from its zero position, no motion would be transmitted to wire 142; but when the pin 134 is spaced below the pin 139 as shown in Fig. 4B, or in case the pin 134 is spaced above the pin 139, which would be the case when knob 165 is rotated 180° from the position shown in Fig. 1, and if the wind velocity knob 167 were then rotated, motion would be transmitted to wire 142.

Wire 142 moves lever 6 by means of pin 22, lever 6 turning on the pin 7. The reason why no motion is transmitted to wire 142 and lever 6 when the wind direction knob 165 is rotated 90° from the position shown in Fig. 1 is because the wind would be blowing at right angles to the plane, and neither advancing or retarding its speed. It is, therefore, apparent that the lever 6 is controlled in part by the wind velocity and the wind direction, and these elements are, therefore, to be taken into consideration in the movement of the true course ground speed pointer 36 and the

total distance pointer 54 for both of these pointers are actuated from the lever 6.

It will be remembered that when the link 146 is actuated by the rotation of the wind velocity knob 167, link 135 mounted on the pin 138 of the link 146 actuates the wire 142 through the multiplying mechanism shown in Fig. 4B; that is, assuming that pins 134 and 139 are not in alignment with each other. It will also be remembered that the wire 142 controls the position of pin 22 of lever 6, that rack 2 controls the position of pin 7 of lever 6, and that wire 77 controls the position of pin 25 of lever 20, so that the pin 24 of lever 20 is controlled by the wire 142, the wire 77, and the rack 2, and the movement of this pin 24 controls the true course ground speed pointer 36 and the total distance pointer 54.

However, both pins 22 and 25 are not always moved when the wind velocity knob 167 is rotated. For instance, suppose the wind direction knob 165 is set as shown in Fig. 1. The pin 134 will then be a considerable distance below the pin 139 as shown in Fig. 4, while the pin 117 will be in alignment with the pin 122. If now the wind velocity knob 167 were rotated from its zero position the multiplying mechanism shown in Fig. 4B will actuate the wire 142 and lower the pin 22; but since the pins 117 and 122 are in alignment with each other, the multiplying mechanism shown in Fig. 4A will not actuate the wire 125 and the pin 25 remains stationary. If the wind direction knob 165 were rotated 90° clockwise from the position shown in Fig. 1, the pin 134 would be raised into alignment with pin 139, so that the wind velocity knob 167 would impart no motion to pin 22. However, when knob 165 is rotated, as above described, the pin 117 would be lowered below the pin 122 as shown in Fig. 4A; and if knob 167 were then rotated from its zero position, the wire 125 would be actuated to lower the pin 25.

If the wind direction knob 165 were rotated 180° from the position shown in Fig. 1, the pin 134 would be raised as much above pin 139 as it is below it in Fig. 4B, while pin 117 would be moved into alignment with its pin 122. If now the wind velocity knob 167 were actuated, the pin 25 remains stationary while the pin 22 is raised.

If the wind direction knob 165 were rotated clockwise 270° from its position shown in Fig. 1, the pin 139 would be in alignment with pin 134 while pin 117 would be raised above the pin 122. If now the wind velocity knob 165 were rotated from its zero position the pin 22 would remain stationary and pin 25 would be lowered.

However, when the wind direction knob 165 is moved to any position other than the four positions above mentioned, and the wind velocity knob 167 is actuated, both pin 22 and pin 25 would be actuated in accordance with the position into which knob 165 is set and in accordance with the extent of rotation of wind velocity knob 167. In other words, the pin 25 is not actuated by the wind velocity knob 167 in two cases; that is, when the wind direction knob 165 is in the position shown in Fig. 1 or when it is rotated 180° from that position; but in both of these cases the pin 22 is actuated when the wind velocity is actuated. Conversely the pin 25 is actuated by the rotation of the knob 167 when the wind is blowing at a right angle to the direction of the travel of the ship, and the pin 22 is not actuated under these conditions.

It is therefore apparent that the true course

ground speed pointer 36 is controlled by (1) true airspeed knob 163 as shown in Fig. 3, (2) wind direction knob 165 as shown in Fig. 4, and (3) wind velocity knob 167 as shown in Fig. 4. The true course in degrees (C), the wind direction (W), and the drift angle in degrees (D) are all set by the knob 165 and the disc 166. As above stated, the true course ground speed may be calculated by the following formula:

$$V_g = V_a + V_a(\cos D - 1) \pm V_w \cos(C - W) \quad \text{Formula #2}$$

V_a is indicated by the vertical movement of rack 2.

15 Cos D-1 corresponds to the vertical movement of wire 91 and is indicated by the relative positions of pins 13 and pin 74, cos D-1 being 0 when the pins 13 and 74 are in direct alignment.

20 The multiplication of V_a by $(\cos D - 1)$ is accomplished on arms and links 58, 70, 71, and 75, which is the multiplying mechanism shown in Fig. 3D.

25 V_w is accomplished by the vertical movement of point 138.

20 Cos (C-W) is accomplished by the movement of wire 111 controlled by point 112.

25 The multiplication of V_w by $\cos(C - W)$ is accomplished on the multiplying mechanism shown in Fig. 4B.

30 The addition of $\{V_a\} + \{V_w \cos(C - W)\}$ is accomplished on lever 6.

The addition of

$$\{V_a(\cos D - 1)\} + \{V_a + V_w \cos(C - W)\}$$

35 which is V_g , is accomplished on lever 20.

The total distance pointer 54 is controlled by (1) true airspeed knob 163 as shown in Fig. 3, (2) wind direction knob 165 as shown in Fig. 4, (3) wind velocity knob 167 as shown in Fig. 4, and

40 (4) time as shown in Fig. 3. It will be noted that the first three of these elements are identical with the parts used in the calculation of the true course ground speed and that in calculating total distance, time has been taken into consideration.

45 Obviously the total distance (d) is the true course ground speed V_g multiplied by time (t). That is, $d = V_g t$. Formula #4.

50 If it is desired to know the time it will take to fly a known total distance, the operator would set the true airspeed knob 163, the wind direction knob 165 and the wind velocity knob 167. He would then set the time knob 164 until the total distance pointer 54 indicated the known total distance, and he would then read the time 55 on the dial behind the knob 164.

55 As above explained, the true course ground speed V_g is calculated by lever 20, which actuates lever 26 carrying pin 38, so that V_g is accomplished by the vertical movement of pin 38. The

60 time factor is entered by the movement of pins 105 or 45, Fig. 3. The multiplication of V_g by t , which is (d) , is accomplished by the multiplying mechanisms 37, 40, 43, 44, and 47 shown in Fig. 3A.

65 The indicated airspeed pointer 49 is controlled by (1) true airspeed knob 163 as shown in Fig. 3, (2) altitude knob 169 as shown in Fig. 5, and (3) air temperature knob 170 as shown in Fig. 5. The indicated airspeed may be calculated by 70 the following formula:

$$V_i = V_a + V_a(\sigma^{1/4} - 1) \quad \text{Formula #3}$$

V_a is accomplished by the vertical movement of pin 57.

75 $\sigma^{1/4} - 1$ is denoted by the relative positions of

pins 65 and 66, the pin 65 being controlled by the air temperature and altitude knobs.

The multiplication of V_a by $(\sigma^{1/2}-1)$ is accomplished on arms and links 56, 52, 63, 67, and 152, as shown in Fig. 3C.

The addition of $V_a + V_a (\sigma^{1/2}-1)$, which is V_i on indicated airspeed, is accomplished on link 5 through wire 68.

The pilot, being familiar with his plane, would know the best indicated airspeed to fly so that in practice he would determine true airspeed by first entering the known values for air temperature by knob 170 and altitude by knob 168 and would then rotate the true airspeed knob 163 until the indicated airspeed pointer 19 showed the proper value for the operation of that plane. He would then read the true airspeed on the dial behind the true airspeed knob 163.

The drift angle pointer 36 is controlled by (1) true airspeed knob 163 as shown in Fig. 3, (2) wind direction knob 165 as shown in Fig. 4, and (3) wind velocity knob 167 as shown in Fig. 4.

The drift angle (D) may be computed by the following formula:

$$D = \sin^{-1} \frac{V_w \sin (C-W)}{V_a}$$

Formula #1.

The knob 163 controls the true airspeed setting (V_a). The knob 165 controls the wind direction setting (W), as well as course (C), and the wind velocity knob 167 controls the wind velocity setting (V_w).

$\sin^{-1}$ is accomplished by pin 90.

V_w is accomplished by the vertical movement of rack 144.

$\sin (C-W)$ is accomplished by the movement of wire 109 actuated by pin 110.

The multiplication of V_w by $\sin (C-W)$ is accomplished on arms and links 116, 113, 118, 119, and 123 as shown in Fig. 4A.

V_a is accomplished by the vertical movement of link 55 actuated by rack 2.

The multiplication of

$$\left\{ V_w \sin (C-W) \right\} \text{ by } \frac{1}{V_a}$$

which is $\sin D$, is accomplished on links and arms 60, 78, 79, and 83 as shown in Fig. 3E.

The solution of the expression

$$\sin^{-1} \text{ by } \frac{V_w \sin (C-W)}{V_a}$$

which is the angle D, is accomplished by the movement of pin 90 on arm 66.

With the arrangement of the variables as incorporated in this flight computer, it becomes possible to calculate a wide variety of problems. As an illustration, suppose the operator enters the values for true course, wind direction, wind velocity, altitude, air temperature, and time of flight and knows the desired indicated airspeed. If he will now turn the true airspeed knob until the correct indicated airspeed is indicated, the machine will calculate the following results: Drift angle, true course ground speed, total distance flown and true airspeed.

As another example, suppose the operator enters the values for true course, wind direction, wind velocity, altitude, air temperature and time of flight and knows the total distance to be flown. If he will now adjust the true airspeed knob until the total distance pointer reads the correct total distance, the indicated airspeed pointer will show the necessary indicated air-

speed to be maintained in order to fly a given course in a specified time.

Obviously, many other problems can be solved with this calculator, and the above are given as simply representative examples.

Obviously the relative lengths of the various arms and levers and the position of the pivot points on which the various levers turn are material, but their relative lengths and positions 10 are as shown in the drawings, the said drawings being made substantially to scale insofar as the relative lengths of the various levers and links and the position of their pivotal points are concerned.

15 I realize that many changes may be made in the specific form of the invention shown herein without departing from the spirit and scope thereof; and I, therefore, desire to claim the same broadly except as I may limit myself in the following claims.

Having now described my invention, I claim:

1. In a computer, an air temperature setting means, an altitude setting means, a multiplying mechanism, means to actuate a part of said multiplying mechanism according to the setting of both of said setting means, a true airspeed setting means to actuate another part of said multiplying mechanism, said multiplying mechanism serving as a means to multiply a function of altitude and air temperature by true airspeed, a lever, means to move one end of said lever by said multiplying means, means to move the other end of said lever according to the value set by true airspeed setting means, an indicator and means to operate said indicator from said lever.

2. In a computer, a wind direction setting means, means controlled thereby to determine the value $\sin (C-W)$ where W is the direction the wind is blowing relative to north and C is the direction in which a movable object heads, means to enter the wind velocity value V_w , means controlled by said two means to multiply V_w by $\sin (C-W)$, means to enter the true airspeed V_a , means controlled by said true airspeed entering means and by said multiplying means to divide $V_w \sin (C-W)$ by V_a , means for converting the value

$$\frac{V_w \sin C-W}{V_a}$$

50 to the value of the angle represented thereby, and an indicator to indicate the resulting value.

3. In a computer, a calculating mechanism comprising a value indicator, a plurality of settable value entering elements, a device manually settable to register the result of a calculation, and mechanism for determining the correct position to which said device should be set for any given values entered by said value entering elements and indicated by said indicator, respectively, said mechanism including a lever pivotally connected intermediate its ends to said indicator, an operating connection between one end of said lever and said device, a movement multiplying linkage, an operating connection between the other end of said lever and said multiplying linkage, an operating connection between said device and said multiplying linkage, a second lever pivotally connected intermediate its ends to said multiplying linkage, an operating connection between one of said value entering elements and one end of said second lever, and an operating connection between the other of said value entering elements and the opposite end of said second lever.

4. In a computer of the class described, calculating mechanism comprising a value indicator, a plurality of settable value entering elements, a device manually settable to register the result of a calculation, and mechanism for determining the correct position to which said device should be set for any given values entered by said value entering elements and indicated by said indicator, respectively, including means controlled by said device for imparting to said indicator an adjustment directly proportional to the magnitude of the setting movement of said device, means controlled by said value entering elements for adding values entered by the setting thereof, and means controlled by said device and by said adding means, jointly, for imparting to said indicator an adjustment proportional to the magnitude of the product of a multiplication of the sum of the values entered by the setting of said value entering element multiplied by the value registered by said result registering device.

5. In a computer, setting means to enter velocity, a first lever having one end actuated an amount directly proportional to the value entered by said setting means, a second velocity setting means, a wind direction setting means, means to multiply the value entered by said second velocity setting means by a cosine value dependent upon the extent of the actuation of said wind direction setting means, means to actuate the other end of said lever an amount corresponding to said product, a second lever having one end thereof pivoted to an intermediate part of said first lever, means jointly controlled by all of said setting means for adjusting the other end of said second lever, and an indicator actuated by said second lever.

6. In a computer, setting means to enter velocity, a first lever having one end actuated an amount directly proportional to the value entered by said setting means, a second velocity setting means, a wind direction setting means, means to multiply the value entered by said second velocity setting means by a cosine value dependent upon the extent of the actuation of said wind direction setting means, means to actuate the other end of said lever an amount corresponding to said product, a second lever having one end thereof pivoted to an intermediate part of said first lever, means controlled by all of said setting means to actuate the other end of said second lever an amount corresponding to correlated values of all three of said setting means, a third lever actuated by said second lever, means to enter time, means to multiply the value of the movement of the third lever by the value entered by said time setting means and an indicator actuated by said last named multiplying means.

7. In a computer, means for entering a linear value, means for entering an angular value, a pair of multiplying mechanisms each comprising a pair of adjustable input members, an output member, and mechanism for transmitting the movement of each input member to said output member in an amount so modified by the adjustment of the other input member as to position the output member in accordance with the product of values represented by the adjustment of the input members, means controlled by said linear value entering means for entering identical multiplicand values in both of said multiplying mechanisms, and means controlled by said angular value entering means for entering complementary multiplier values in said multiplying mechanisms respectively; whereby the output members of said multiplying mechanisms regis-

ter vectorial components of the linear value entered by said linear value entering means.

8. In a trigonometrical computer, separate means for entering linear values corresponding to two sides of a triangle, means for entering an angular value corresponding to the supplement of a non-included angle of said triangle, multiplying means controlled by one of said linear value entering means and by said angular value entering means, dividing means controlled by the other of said linear value entering means and by said multiplying means, and means controlled by said dividing means for registering an angular value corresponding to the other non-included angle of said triangle.

9. In a trigonometrical computer, separate means for entering linear values corresponding to two sides of a triangle, means for entering an angular value corresponding to the supplement of a non-included angle of said triangle, a pair of multiplying mechanisms, means controlled by one of said linear value entering means for entering identical multiplicand values in both of said multiplying mechanisms, means controlled by said angular value entering means for entering the values of the sine and cosine of said angular value in said multiplying mechanisms, respectively, dividing means controlled by the other of said linear value entering means and by a first one of said multiplying mechanisms, multiplying means controlled by said other of said linear value entering means and said dividing means, and means for adding the products registered by said multiplying means and by the second one of said multiplying mechanisms and the linear value entered by the said other of said linear value entering means and registering a linear value corresponding to the third side of said triangle.

10. In a computer, means for entering a linear value, means for entering an angular value, a pair of multiplying mechanisms each comprising a pivotally supported guide link, a first movable link having a pivotal connection with said guide link radially spaced from the pivotal support thereof, a second movable link having a pivotal connection with said first link radially spaced from the pivotal connection of said first link with said guide link, and a movable member having a pivotal connection with said second link radially spaced from the pivotal connection between said links; all of said radial spacings being equal; means controlled by said linear value entering means for imparting identical movements to one pivotal connection between said links in each of said multiplying mechanisms, means controlled by said angular value entering means for imparting respectively complementary movements to the other pivotal connection between said links in each of said multiplying mechanisms, and means controlled by the respective movable members of said multiplying mechanisms for registering respective vectorial components of the linear value entered by said linear value entering means.

11. In a computer, means for entering a linear value, means for entering an angular value, a pair of multiplying mechanisms each comprising a pivotally supported guide link, a first movable link having a pivotal connection with said guide link radially spaced from the pivotal support thereof, a second movable link having a pivotal connection with said first link radially spaced from the pivotal connection of said first link with said guide link, and a movable member having a pivotal connection with said second link radially spaced from the pivotal connection between said links in each of said multiplying mechanisms, and means controlled by the respective movable members of said multiplying mechanisms for registering respective vectorial components of the linear value entered by said linear value entering means.

spaced from the pivotal connection between said links; all of said radial spacings being equal; means controlled by said linear value entering means for imparting identical movements to one pivotal connection between said links in each of said multiplying mechanisms, means controlled by said angular value entering means for imparting to the other pivotal connection between said links in one of said multiplying mechanisms a movement proportionate to the sine of the angular value entered by said angular value entering means, means controlled by said angular value entering means for imparting to the other pivotal connection between said links in the other of said multiplying mechanisms a movement proportionate to the cosine of the angular value entered by said angular value entering means, and means controlled by the respective movable members of said multiplying mechanisms for registering respective vectorial components of the linear value entered by said linear value entering means.
